US0D1057703S

(12) **United States Design Patent** (10) **Patent No.:** **US D1,057,703 S**
(45) **Date of Patent:** **** Jan. 14, 2025**

(54) **NECK HANGING MAGNETIC SUPPORT**

(71) Applicant: **ShenZhen Neewer Technology Co., Ltd.**, Guangdong (CN)

(72) Inventor: **Jia Liu**, Dongguan (CN)

(73) Assignee: **Junxing Zhizao (Dongguan) Co., Ltd** (CN)

(***) Term: **15 Years**

(21) Appl. No.: **29/954,453**

(22) Filed: **Jul. 26, 2024**

(30) **Foreign Application Priority Data**

CLAIM

The ornamental design for a neck hanging magnetic support, as shown and described.

DESCRIPTION

FIG. 1 is a front right perspective view of a neck hanging magnetic support, showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines of even length depict portions of the neck hanging magnetic support that form no part of the claimed design.

1 Claim, 7 Drawing Sheets
